UNITED STATES PATENT OFFICE.

PATER IVERSON, OF KINDRED, NORTH DAKOTA.

WRENCH.

1,234,765.

Specification of Letters Patent.

Patented July 31, 1917.

Application filed October 5, 1916. Serial No. 123,866.

To all whom it may concern:

Be it known that I, PATER IVERSON, a citizen of the United States, residing at Kindred, in the county of Cass and State of North Dakota, have invented certain useful Improvements in Wrenches, of which the following is a specification; reference being had therein to the accompanying drawing.

The invention relates to a wrench and 10 more particularly to the class of ratchet wrenches.

The primary object of the invention is the provision of a wrench of this character wherein the construction thereof permits the 15 convenient loosening or tightening of burs, teeth, tines or nuts within the cylinder of a threshing machine which are inaccessible for the use of an ordinary wrench and the proper leverage can be had for operation.

Another object of the invention is the provision of a wrench of this character wherein the construction thereof is novel in form and the ratchet mechanism therein can be 20 readily adjusted for permitting reverse action of the wrench either in loosening or tightening parts.

A further object of the invention is the provision of a wrench of this character wherein the handle stem carries a crank 25 which is swiveled in the head of the wrench so that the same can be properly manipulated when the wrench is in use for the tightening or loosening of parts, the said wrench being designed particularly for use 30 in tightening and loosening burs or spikes in a cylinder in a threshing machine.

A still further object of the invention is the provision of a wrench of this character which is simple in construction, thoroughly 40 reliable and efficient in its operation, strong, durable, readily and easily adjusted and inexpensive in manufacture.

With these and other objects in view the invention consists in the features of construction, combination of elements, and arrangement of parts as will be hereinafter fully described, illustrated in the accompanying drawings, and pointed out in the claims hereunto appended.

50 In the accompanying drawings:

Figure 1 is a fragmentary perspective view of a portion of the cylinder in the threshing machine showing the wrench constructed in accordance with the invention 55 applied.

Fig. 2 is a top plan view of the wrench.

Fig. 3 is a vertical longitudinal sectional view through the head of the wrench.

Fig. 4 is a sectional view on the line 4—4 of Fig. 3.

Fig. 5 is a perspective view of the chuck member of the wrench.

Fig. 6 is a perspective view of the handle stem.

Similar reference characters indicate corresponding parts throughout the several views in the drawings.

Referring to the drawings in detail, A designates a portion of a bar or slat and B the bur, tooth or tine mounted therein of 70 the cylinder of a threshing machine which is of the usual well-known construction and these parts being merely shown to illustrate the application and manner of use of the wrench hereinafter fully described.

The wrench comprises a head 10 in one end of which is rotatably mounted a ratchet hub 11 formed with a chuck 12 at one end while the opposite end is reduced to provide a central boss 13 for receiving a cap-like 80 collar 14 which is held on the boss by means of a retaining pin 15 which is passed transversely through the boss 13. In this manner the hub is rotatably held within the head 10 while rotatably supported in the other 85 end of said head is a stud 16 of a crank 17 formed at the end of a handle stem 18 to which is detachably connected a handle hereinafter described.

The head 10 is formed with a bifurcation 90 19 opening through one end thereof in which is received the block end 20 of a guide pin 21 the latter being passed through a transversely disposed web 22 formed in the head 10. Telescoped upon this pin 21 is a 95 slideable and rotatable locking bolt 23 which is formed at one end with a bevel latch tooth 24 to engage in any one of the series of grooves 25 forming the ratchet surface of the ratchet hub 11 so that the latter will 100 be locked against rotation in one direction in the head 10. By reason of the formation of the tooth 24 on the bolt 23 the hub 11 will be freed for rotation in the reversed direction or the head 10 can revolve on the hub 11 in one direction yet will be locked 105 against reverse movement until the bolt 23 is adjusted to permit the reverse revolving of the head or the reverse rotation of the hub 11 therein.

The guide pin 21 is formed with a transverse slot 26 in which engages a cross pin 27

formed in a follower ring 28 slidably fitted upon said guide pin 21. To this cross pin 27 is connected one end of a coil retractile spring 29 which has its opposite end fixed in 5 the guide pin 21 so as to exert a pull upon the ring 28 which acts upon the bolt 23 to positively move the same into locking engagement with the hub 11 in the head 10. The bolt 23 at the end next to the ring 28 is 10 exteriorly knurled as at 30 to afford a hand grip so that on slightly retracting the bolt upon the guide pin 21 it can be rotated thereon for changing the position of the bolt to reverse the feed of the ratchet hub 11 and the head 10 as will be clearly apparent.

The web 22 is provided with an opening 22' to accommodate the reduced portion 31 formed on the block end 20 of the guide pin 20 21 for the proper assembling of the block end 20 within the head 10. This block end 20 is also formed with an opening 23' to receive the stud 16 of the crank 17 formed with the stem 18 for the handle.

25 The handle comprises a bar 33 which is formed with squared openings 34 and 35 centrally thereof and at one end respectively of the same. Either of these openings 34 or 35 is adapted to receive the squared end 36 30 of the stem 18 and in this manner the handle bar is fastened thereon. The handle bar by reason of the adjustability thereof upon the stem permits the proper leverage to be had in manipulating the wrench for the 35 tightening or loosening of the bur B in the bar A, the chuck being adapted for adjustable engagement with the headed end of the bur B as is clearly shown in Fig. 1 of the drawings.

40 Loose upon the stem 18 next to the crank 17 is a sleeve 37 which is held against displacement longitudinally upon the stem by means of the collar 38 thereon and this sleeve 37 is formed with a stop wing or extension 39 which is engageable with the head 10 so that on manipulating the handle bar the crank can be properly turned for 45

the swinging of the head 10 which acts upon the chuck 12 for the turning thereof when engaged with the bur B in the bar 50 A, it being understood of course that the bar carries a number of burs or spikes B and is only a portion of one of a series of bars of the cylinder employed in a threshing machine. The make-up of the cylinder prevents the use of an ordinary wrench but by the employment of the wrench hereinbefore described the burs or spikes in the bars of the cylinder can be readily loosened or tightened as will be obvious. 55

On changing the bolt 23 for rotating the same upon the guide pin 21 the ratchet mechanism of the wrench is reversed for the proper manipulation of the wrench.

From the foregoing it is thought that the 60 construction and manner of use of the wrench will be clearly understood and therefore a more extended explantion has been omitted.

What is claimed is:

1. A wrench of the character described comprising a head, a chuck rotatably mounted in the head, reversible ratchet lock mechanism within the head and coöperative with the chuck, a crank stem having its crank 75 rotatably connected with the head, said stem forming a means for operating the wrench, and a sleeve rotatably mounted on the stem and having an extension engageable with the head. 80

2. A wrench of the character described comprising a head, a chuck rotatably mounted in the head, reversible ratchet lock mechanism within the head and coöperative with the chuck, a crank stem having its crank rotatably connected with the head, said stem forming a means for operating the wrench, a sleeve rotatably mounted on the stem and having an extension engageable with the head, and a ratchet hub formed on the 85 chuck and journaled in the head for co-operation with the ratchet mechanism. 90

In testimony whereof I affix my signature.
PATER IVERSON.
